UNITED STATES PATENT OFFICE.

BENJAMIN W. ALPINER, OF KANKAKEE, ILLINOIS.

COLLAPSIBLE LAPBOARD FOR CARD PLAYERS.

Application filed May 13, 1921. Serial No. 469,222.

To all whom it may concern:

Be it known that I, BENJAMIN W. ALPINER, a citizen of the United States, residing at 222 So. East Avenue, Kankakee, in the county of Kankakee and State of Illinois, have invented certain new and useful Improvements in Collapsible Lapboards for Card Players, of which the following is a specification.

10 This invention relates to new and useful improvements in lap-boards for card players.

15 The primary object of this invention is to provide a simple and economical device of this character adapted to be placed on the lap of the player to prevent any cards from falling on the floor.

20 A further object of my invention is to provide a lap-board which is collapsible and may be folded into very compact form during transportation or when not in use.

25 With the foregoing and other objects in view that will appear as the nature of the invention is better understood, the same consists in the novel features of construction, combination and arrangement of parts illustrated in the drawings and more particularly pointed out in the appended claim.

30 In the accompanying drawings, which are for illustrative purposes only and are therefore not drawn to scale:—

Fig. 1 is a plan view of my improved lap-board, extended or ready for use.

Fig. 2 is a horizontal section.

35 Fig. 3 is a longitudinal section, taken on line 3—3 of Fig. 1.

Fig. 4 is a transverse section, taken on line 4—4 of Fig. 1.

40 Fig. 5 is a detail perspective view of one of the end strips or slats.

Fig. 6 is a similar view of one of the longitudinal strips or slats and Fig. 7 is a detail perspective view of the device collapsed or folded.

45 Referring to the drawings for a more particular description of the invention and in which drawings like parts are designated by like reference characters throughout the several views, the device comprises what 50 may be termed a board 1 of leather, leatherette, cloth, canvas or other flexible material preferably formed from a single strip or sheet doubled centrally upon itself (see Fig. 4) to form the top and bottom members 2 and 3, respectively. In carrying out my invention, these members are stitched

together at equal intervals apart, by double rows of parallel stitching, as 4, to provide the longitudinally disposed transversely spaced sleeves or pockets 5 adapted to receive flat strips or slats 6 of wood, pasteboard, aluminum or other rigid or semi-flexible material.

60 The board 1 is also provided at opposite ends with the transversely disposed sleeves or pockets 7 adapted to receive the strips or slats 8. The ends of the top and bottom members of the board as well as the side edges 9 thereof, are stitched together, as at 10, 11 and 12, respectively, the seam 12 not extending the full length of the board, whereby the adjacent ends of the sleeves or pockets 7 are left open, as at 14, to provide for the introduction and removal of 65 the end strips or slats.

70 In practice, to use the device, it is only necessary to unfold or extend the board from the folded or collapsed position shown in Fig. 7 and insert the end strips or slats 8. It will be noted that the end strips 8 not only provide the required rigidity at 75 the ends of the board but hold the longitudinal strips 6 against longitudinal displacement.

75 By sewing the top and bottom members 2 and 3 of the board together by double rows of parallel stitching, as shown, sufficient spaces are provided between the respective sleeves or pockets 5 to permit folding of the device into very compact form, 80 as illustrated in Fig. 7, after first removing the end strips or slats 8. The use of my device will prevent any cards that are “dropped” by the player during the game 85 from falling on the floor with the attendant annoyance, inconvenience and delay caused thereby.

90 From the foregoing description taken in connection with the drawings, it is thought that the construction, operation and advantages of my invention will be readily understood without requiring a more extended explanation.

95 Having described my invention, what I claim as new and desire to secure by Letters Patent, is:—

100 A device of the character specified, comprising a lap-board formed of flexible material and provided in its body portion with a plurality of longitudinally disposed transversely spaced sleeves or pockets and at each 105 end with a transversely disposed sleeve or

5 pocket, strips of rigid or semi-flexible material arranged in said longitudinal sleeves or pockets and other similar strips arranged in said transverse sleeves, the inner edges of the transverse strips fitting against the ends of the longitudinal strips and holding the latter against longitudinal displacement

and the transverse sleeves or pockets being open at one end, to provide for the removal of the end strips preparatory to collapsing 10 or folding the device.

In testimony whereof I affix my signature.

BENJAMIN W. ALPINER.
